EXTENSION TABLE SLIDE ASSEMBLY

Richard R. Lowe, San Francisco, Calif., assignor
to Beatrice Minnie Lowe, Ruth Marie Jacobs,
Clifford Osborne Lowe, Hazel Adelaide Berg,
and himself, as joint tenants

Application June 19, 1945, Serial No. 600,266

6 Claims. (Cl. 311—73)

1

An object of my invention is to provide an extension table slide assembly which is an improvement over my co-pending application Serial No. 527,581, filed March 22, 1944. In the co-pending case I show the central H-shaped member provided with stops that are welded to the member at predetermined points. I further show tongues slidable in channels carried by the member, and these tongues have stops secured thereto, the stops extending from the ends of the tongues to points disposed near the centers of the tongues. In the present form of the invention the stops on the H-shaped member are struck up from the material forming the member and this adapts the device to be made from sheet metal stampings. The tongues also have stops struck up from the material from which they are formed and these stops do not extend to the ends of the tongues as shown in my co-pending case.

In the co-pending case, each tongue is reinforced by a longitudinally extending and centrally disposed rib that is arcuate in cross section. Each tongue in my present invention has channel-shaped runners that are slidably received in the channels of the central member and therefore the channel-shaped runners provide the necessary rigidity for the tongue and further provide the necessary space between the tongue and the central member in which the tongue stops move.

A still further object of my present invention is to provide an equalizing means for the tongues and central member, this means including an equalizing gear rotatably carried by the central member and meshing with racks that are supported by the table top rails. I provide novel means for maintaining the gear in mesh with the teeth of both racks at all times.

Other objects and advantages will appear in the following specification, and the novel features of the device will be particularly pointed out in the appended claims.

My invention is illustrated in the accompanying drawings forming a part of this application, in which:

Figure 1 is a perspective view of the central support;

Figure 2 is a perspective view of one of the tongues;

Figure 3 is a top plan view showing the tongues operatively connected to the central member and further illustrating how the device is attached to a table construction;

Figure 4 is a transverse section taken along the line 4—4 of Figure 3;

Figure 5 is a schematic view comparing the over

2

all length of the device when the tongues are in open position and when they are in closed position;

Figure 6 is a top plan view of the device showing an equalizing assembly operatively connected thereto; and

Figure 7 is a section taken along the line 7—7 of Figure 6.

While I have shown only the preferred forms of my invention, it should be understood that various changes or modifications may be made within the scope of the appended claims without departing from the spirit and scope of the invention.

In carrying out my invention, I provide a central H-shaped member indicated generally at A and this member is composed of two identical U-shaped members shown at B and B¹. The upper member B is channel-shaped and has a central web 1 and side portions 2 and 3. The side 2 has a channel 4, while the side 3 has a channel 5.

The lower U-shaped member B¹ is inverted and has a central web 6 that abuts the web 1 and is spot welded or otherwise secured thereto. Side portions 7 and 8 of the member B¹ extend from the web 6 so that the portion 7 lies in the same plane as the portion 2 of the member B and the portion 8 lies in the same plane as the portion 3. The side portion 7 has a channel 9 that faces the channel 4, while the side portion 8 has a channel 10 that faces the channel 5. The resulting structure is H-shaped in cross section with the pair of channels 4 and 9 being adapted to slidably receive a tongue and the pair of channels 5 and 10 being adapted to receive another tongue. The members B and B¹ are of identical construction.

Before describing the structure of the tongues it is best to set forth the position of the stops provided on the side portions of the central member A. The U-shaped member B has a stop 11 struck up from the side 3, the stop extending outwardly from the outer surface of the side portion 3. The stop 11 is punched out of the side and has an arcuate edge 11a that functions as the stop. The stop 11 is disposed at one end of the side 3.

The side portion 2 has a similarly shaped stop 12 disposed at the opposite end of the member B, see Figure 1, and the stop 12 has an arcuate edge 12a that is struck up from the side 2 and projects outwardly from the outer surface of the side. In like manner the U-shaped inverted member B¹ has a stop 13 struck up from the side portion 8 and having an arcuate edge 13a. The other side 7 of the member B¹ has a stop 14 with

an arcuate edge 14a and the stop 14 is disposed at the opposite end of the member B1 from that carrying the stop 13. It will be seen that when the member B1 is turned into an upright position, the stops 13 and 14 will be arranged in the same positions as the stops 11 and 12.

In Figure 2 I show a tongue C that has a channel shaped runner 15 disposed along one edge and a channel shaped runner 16 disposed along the other edge. A central web 17 interconnects the channel runners 15 and 16 and this central web has two stops 18 and 19 disposed near the center of the tongue. In actual practice the stop 19 will have its arcuate edge 19a positioned to the right of the central line 20 that bisects the length of the tongue, see Figure 2, and the stop 18 will have its arcuate edge 18a spaced from the stop 19 and lying on the same side of the line 20 as the stop 19, but being disposed closer to the center line than the stop 19.

Figure 3 shows the central member A with the tongue C slidably received in the pair of channels which includes the top channel 4. A second tongue C1 is similar in construction to the tongue C and is slidably received in the pair of channels which includes the top channel 5. The tongue C has openings 21 therein for receiving screws 22 that connect a table top rail 23 to the tongue. In like manner a table top rail 24 is connected to the tongue C1 by screws 25. Figure 3 further shows a table top section 26 secured to the table top rail 23 by screws 27 and a table top section 28 secured to the table top rail 24 by screws 29. The central member A has its inverted U-shaped member B1 receiving the side rail 30 of the table and in this way the device is supported by the table frame.

There are two of these devices for each table, one being mounted on each side rail 30 of the table frame and before describing the operation of the device, it might be well to set forth the construction of the equalizing mechanism which is used in connection therewith. Referring to Figures 6 and 7 it will be seen that the side rail 30 of the table frame not only supports the central member A but also supports a strap 31 that has one end connected to the side rail 30 by a screw 32 and has its other end provided with an arcuate slot 33 that slidably receives a screw 34, the screw being secured to the side rail 30. The side rail is recessed at 35 for receiving the member A.

Figures 6 and 7 show the strap 31 rotatably carrying an equalizing gear 36 that is rotatably connected to the strap by a rivet 37 or other suitable fastening means. The table top rail 23 has a rack 38 secured to its top and this rack meshes with the gear 36. In like manner, the table top rail 24 has a rack 39 on its top which meshes with the gear 36.

One feature of the equalizing device is the novel means I employ for maintaining the gear 36 in constant mesh with the racks 38 and 39. Angle-shaped guard members 40 and 41 are secured to the table top rails 23 and 24, respectively, by screws 42 and 43. The guard members 40 and 41 overlie the teeth of the racks 38 and 39 and therefore overlie the tooth portions of the gear 36 that actually mesh with the racks. This feature is clearly shown in Figure 6 and the members 40 and 41 prevent the gear from jumping out of mesh with the racks. The purpose of the arcuate slot 33 is to permit a slight lateral movement of the straps 31, so that the gear

can move laterally if necessary and have its teeth mesh with the racks at all times.

From the foregoing description of the various parts of the device, the operation thereof may be readily understood.

Figure 3 shows the extension table slide assembly in closed position with the table top sections 26 and 28 abutting each other and the tongues C and C1 extended so that the stop 19 on the tongue C strikes the stop 14 on the member A and the stop 19 on the tongue C1 strikes the stop 13 on the member A. Figure 5 shows the position of the tongues C and C1 when they are in closed position and shows the over all length of the device extending over a greater distance than when the tongues are in open position.

In opening the table, the table top sections 26 and 28 are pulled apart and will carry with them the table top rails 23 and 24, respectively. The rail 23 will move the tongue C along the member A so that the tongue will be projecting from the right hand end of the member A when looking at Figure 5 rather than from the left hand end. In the same way the rail 24 will move the tongue C1 so that it will project from the left hand end of the member A and the stop 18 on the tongue C1 will engage with the stop 11 on the member A. A greater support is therefore provided for the tongues C and C1 when the table sections are in open position than when they are in closed position. It is obvious that a greater support is needed for the table top sections when they are open than when they are closed.

The equalizing mechanism shown in Figures 6 and 7 will cause the tongues C and C1 to move uniformly during the opening and closing of the table top sections. The guard members 40 and 41 will hold the gear 36 in mesh with the racks 38 and 39 at all times. A perfectly balanced table is made possible at all times by using the equalizing mechanism whether the table top sections are in open or closed position or any intermediate position.

I claim:

1. In an extension table slide assembly, a central support having channels on opposite rectangular sides and stops arranged at diagonally opposite corners of each side, and tongues slidably in the channels and each having two stops for contacting with the first-named stops, both tongue stops being disposed near the midway point between the tongue ends and within the same half of the tongue, one tongue stop being farther removed from the midway point than the other tongue stop, the tongues being movable beyond either end of the central support and the tongue stops cooperating with the first-named stops for limiting the outward movement of the tongues, the tongue stops being so designed that the tongues will project a greater distance beyond the central support when the tongues are moved in opposite directions into one extreme position than when they are extended in opposite directions into the other extreme position.

2. In an extension table slide assembly, a central support having channels on opposite rectangular sides, stops arranged at diagonally opposite corners of each side, tongues slidably in the channel and having stops struck up from the side of the tongue which will face the central support, each tongue stop being aligned with one of the central support stops and designed to strike the first-named central support stops for limiting the movements of the tongues in both

directions, one tongue stop being positioned adjacent to the tongue center and the other tongue stop being positioned farther from the tongue center and on the same half of the tongue as the first tongue stop, the tongues being movable beyond either end of the central support and the tongue stops cooperating with the first-named stops for limiting the outward movement of the tongues, the tongue stops disposed nearest the tongue centers when contacting with their central support stops preventing the tongues from extending so far beyond the ends of the central support as when the other tongue stops contact with their central support stops.

3. In an extension table slide assembly, a central support having channels on opposite rectangular sides, stops arranged on the outer faces of the sides and being disposed at diagonally opposite corners of each side, tongues slidably in the channels and having their central portions throughout the lengths of the tongues spaced from the rectangular sides so that the tongues can move over the stops, stops struck up from the central tongue portions and extending into the space provided between the central tongue portion and the rectangular side, one stop on each tongue being positioned substantially midway between the tongue ends so that substantially one-half of each tongue will project beyond opposite ends of the central support when the tongue stops contact their associate stops on the central support, the other stop on each tongue being spaced from the tongue center so that less than one-half of each tongue will project beyond opposite ends of the central support when the tongues have been moved along the lengths of the channels and project beyond the central support ends opposite from that from which they formerly projected.

4. An extension table slide comprising a central support composed of two identical U-shaped parts with their central webs brought into abutting relation and their sides facing away from each other and forming contiguous rectangularly-shaped sidewalls, each side of each U-shaped part having a channel along its free edge and a stop disposed adjacent to one end, the stops on each U-shaped part being disposed at opposite ends, and two identical tongues, each having channels along their sides slidably received in the channels of the central support and having longitudinally extending webs disposed between the tongue channels and spaced from the support sides, each tongue having stops struck up from the web and extending inwardly, said tongue stops contacting the support stops and limiting

the movement of the tongues in both directions, the tongue stops permitting the tongues to extend a predetermined distance beyond each end of the central support.

5. In combination, a central support having channels on opposite rectangular sides, tongues slidable in the channels and being movable beyond either end of the central support, means for limiting the movement of the tongues in both directions, a table top rail carried by each tongue, a rack carried by each rail, a table frame for supporting the central support, a strap carried by the frame and extending along the top of the support, an equalizing gear rotatably carried by the strap and meshing with the racks, and angle-shaped guards carried by the rails and overlying the rails, said guards also overlying the portions of the gear meshing with the racks, whereby the gear will be held in mesh with the racks at all times.
- 10 6. In combination, a central support having channels on opposite rectangular sides, tongues slidable in the channels and being movable beyond either end of the central support, means for limiting the movement of the tongues in both directions, a table top rail carried by each tongue, a rack carried by each rail, a table frame for supporting the central support, a strap carried by the frame and extending along the top of the support, an equalizing gear rotatably carried by the strap and meshing with the racks, and angle-shaped guards carried by the rails and overlying the rails, said guards also overlying the portions of the gear meshing with the racks, whereby the gear will be held in mesh with the racks at all times.
- 15 25 30 35
- 20 25 30 35
- 25 30 35
- 30 35
